UNITED STATES PATENT OFFICE.

WILLIAM CARVER, OF CLEVELAND, OHIO, ASSIGNOR TO RALPH P. STODDARD, OF LAKEWOOD, OHIO.

BRICK WALL CONSTRUCTION.

Application filed August 30, 1924. Serial No. 735,172.

This invention relates to wall construction and is directed more particularly to a wall formed from bricks such as commonly used for buildings.

- 5 Heretofore it has been the customary practice to construct a brick wall having a thickness of two or more bricks, such thickness depending upon the height of the wall and the stresses and strains to which it was 10 to be subjected. This practice involves the use of a larger number of bricks and also more labor for laying the same than contemplated by a wall constructed in accordance with my invention.
- 15 It is the primary object of the present invention to construct a brick wall whose normal thickness shall be equal to the width of a single brick and which shall be provided with suitable pilaster reinforcements serving 20 also as supports for the finish at definite intervals, and such reinforcements shall constitute an integral part of the wall proper.

Another object is to provide a wall of the aforesaid character which shall include novel 25 means for supporting the girders or joists and also window and other frames commonly used in building construction.

A still further object is to provide a wall of this general character which shall be simple in construction, inexpensive to erect, and which shall be strong and durable and capable of withstanding the stresses usually encountered.

With these and other objects in view, the 35 invention consists in the various novel features of construction and arrangement or combination, all of which will be fully described hereinafter and pointed out in the appended claims.

- 40 In the drawings accompanying and forming a part of this application, Fig. 1 is a perspective view of a corner portion formed by two walls constructed in accordance with my invention; Fig. 2 is a detail vertical sectional view through the wall; Fig. 3 is a perspective view of one course of bricks laid in accordance with my invention; Fig. 4 is a perspective view of an adjacent course of bricks laid in accordance with my invention; Fig. 5 is a fragmentary vertical sectional view 45 through one of the reinforcing pilasters; Fig. 6 is a view similar to Fig. 2 but showing a modified form of construction for supporting the joists and forming a fire stop; Fig. 50 5 is a fragmentary perspective view of a

modified form of construction of the reinforcing pilaster; Fig. 8 is a detail perspective view of one course of bricks used in the construction illustrated in Fig. 6; Fig. 9 is a perspective view of an adjacent course of 60 bricks used in the construction illustrated in Fig. 6; and Fig. 10 is a perspective view showing a modified form of construction employed for supporting the joists.

In building a wall in accordance with my 65 invention, I first lay a course of bricks 1 end to end on a suitable foundation, and at intervals equal to a distance of about two bricks I lay a half brick 2 at right angles to the wall defined by this course. At the end 70 of course 1 where the corner is to be formed, I lay a brick 3 which is of less length than the usual brick and slightly longer than the half bricks 2. A brick 4 is then laid at right angles to the course 1 and in contact with 75 the end of brick 3. A brick 5 is then laid parallel to the course 1 and with its end in contact with brick 4 and another brick 6 is then laid at right angles to brick 4 and with 80 its end flush with the outer surface of this 80 brick. A course of bricks defining the second wall is then formed by laying two bricks 5, end to end, and then a brick 6^a at right angles thereto so that it will occupy a position similar to brick 6. This course is continued to the desired length whereupon a 85 corner is formed, as previously described, and a course defining the third wall is then laid parallel with the first mentioned wall and in a manner similar to that described in 90 connection therewith.

The fourth wall may be constructed in a manner similar to that described in connection with the second wall. It will be understood of course that while I have shown the 95 half bricks 2 and the bricks 6 and 6^a spaced at an interval of two bricks, any suitable spacing distance can be used.

After this first course of bricks is laid, a second course is superimposed thereon and this second course is shown in Fig. 4. The second course is formed by laying a brick 7 on each of the half bricks 2 so that said brick will extend over the joint between bricks 1 and lie flush with the outer surface 100 of these bricks. The space intervening between the bricks 7 is then filled by bricks 8 arranged end to end and superimposed upon bricks 1. The corner of this second course 105 of bricks is formed by arranging a brick 7 110

over the joint formed by brick 3 and adjacent brick 1, and also so that said brick will lie flush with the inner end of brick 5 in the first course. A brick 9 is then laid with its end in contact with brick 7 and the end of this brick will lie flush with the wall defined by brick 4 in the first course. A second brick 7^a is arranged parallel to brick 7 but is disposed in staggered relation with respect thereto and this brick will lie flush with the inner end of brick 6 in the first course. A brick 3^a of substantially the same size as brick 3 is then positioned with its end in contact with brick 9 and with its side in contact with brick 7^a. Three bricks 10 are then laid end to end with respect to brick 3^a and a half brick 11 is then positioned adjacent the third brick 10 and at an interval of two bricks along the wall thus formed.

It will be observed that the second course of bricks just described is substantially identical with the first course shown in Fig. 3 except that a reverse construction is employed. The walls are thus built up using first a course of bricks such as shown in Fig. 3 and then a course such as shown in Fig. 4, alternating such courses until the desired height is obtained.

By referring to Fig. 1 it will thus be noted that each wall is formed with a plurality of reinforcing pilasters 12 which constitute an integral part of the wall.

When the wall has reached a suitable height for laying joists, I then place an angle iron 13 longitudinally of two opposite walls and this angle iron is supported by the reinforcing pilasters 12. The joists 14 will then be supported directly on the angle iron at any suitable distance apart and, if desired, may be connected to the angle iron by suitable anchors or straps 15, each of which is provided with a hooked portion 16 that is adapted to engage the upstanding flange of angle iron 13. From this point the walls may be carried upwardly to any desired distance using the same method of construction as previously described. If desired, the space between the ends of adjacent joists may be filled in with bricks 17 (Fig. 6) and thereby eliminate the use of the anchors or straps 15. These bricks in addition to supporting the joists also form an effective fire stop as they provide a barrier between adjacent joists and thereby shut off the flues defined by the pilasters so that the danger of fire spreading from a lower floor to an upper floor is reduced to a minimum.

The pilasters 12 in addition to reinforcing the walls also serve as convenient supports for fastening the finish work a portion of which is indicated at 12.

In Figs 6 to 9 inclusive I have shown a slightly modified form of construction for forming the reinforcing pilasters. In this

modified form I employ, instead of a half brick 2 or 11, a whole brick 18 which is laid parallel with the wall. The second course of bricks superimposed thereon is identical with the course illustrated in Fig. 4. The result is a reinforcing pilaster having an appearance such as shown in Fig. 6.

In Fig. 10 I have shown a modified form of construction for supporting the joists and which eliminates the use of angle iron supports and permits the use of bricks corbelled over for supporting the same. The wall is built up to the desired height in a manner similar to that already disclosed, four such courses of construction being illustrated in this particular view. At the fourth course a brick 21 is laid at right angles to each supporting pilaster and then a course of bricks 22 is laid at right angles to the wall. On top of this course I then lay a course of bricks 23 which are arranged at right angles to the course 22 and which define a course having a width of two bricks. The courses of bricks 22 and 23 define an inwardly projecting shelf from the wall and serve the double purpose of providing a support for the joists 14^a and also providing a fire stop for the wall, thereby preventing fire from spreading from the lower story to the upper. In other words, these two courses projecting inwardly from the wall shut off the natural flues defined by the reinforcing pilasters. The joists 14^a are supported directly on the course of bricks 23 and the wall is then continued upwardly by laying a suitable number of courses 23^a which completely enclose the ends of the joists and support said stringers in their proper positions. From this point onward the wall is constructed in the manner already referred to.

A wall constructed in accordance with my invention uses a much less number of bricks than formerly required for similar walls and the formation of the reinforcing and supporting pilasters as an integral part of the wall imparts sufficient strength thereto so that the wall is enabled to withstand the ordinary stresses and strains to which it is subjected and the pilasters serve as convenient supports for the finish. No special form or size of bricks are required and in view of the less number of bricks used in its construction, the labor cost of laying the same is also reduced to a minimum. The wall can be easily and quickly erected and suitable provision is made for supporting the joists without difficulty.

Having thus described my invention, what I claim is:

1. A wall corner formed by the intersection of two walls, each wall comprising a plurality of courses of bricks and each course having the bricks laid end to end, alternate courses in one of said walls having

- a brick arranged at right angles to the wall adjacent the corner thereof, a second brick arranged parallel to the first brick in each of said alternate courses, said second brick being staggered with respect to the first brick, and the intermediate courses in the other wall having the corner bricks laid in a manner similar to the corner bricks in said alternate courses but at right angles thereto. 10
2. A wall corner formed by the intersection of two walls, each wall comprising a plurality of courses of bricks, the alternate courses of one wall having the corner bricks projecting at right angles thereto, the intermediate courses in the other wall having the corner bricks laid in a similar manner to the corner bricks in the said alternate courses but at right angles thereto. 15
- 20 3. A wall corner formed by the intersections of two walls, each wall comprising a plurality of courses of bricks, alternate courses in one of said walls having a brick arranged at right angles to the wall of the adjacent corner thereof, a second brick arranged parallel to the first brick in each of said alternate courses but staggered with
- respect thereto and the intermediate courses in the other wall having the corner bricks arranged in like manner but at right angles to the corner bricks in said alternate courses. 30
4. A wall formed from a plurality of courses of standard size bricks and having a thickness equal to the width of one brick, certain of said courses having bricks at 35 definite intervals arranged at right angles to define reinforcing columns and the other courses having a half size brick interposed between said right angularly disposed bricks in said first mentioned course. 40
5. A wall formed of a plurality of courses of standard size bricks each course having the bricks laid end to end, alternate courses of said wall having a brick arranged at right angles thereto and at definite intervals, the intermediate courses of said wall having a brick of half the length of the standard brick interposed between the projecting portions of the first mentioned course. 45 50

In testimony whereof, I hereunto affix my signature.

WILLIAM CARVER.
